UNITED STATES PATENT OFFICE.

ABIJAH WALLACE, OF NEW YORK, N. Y.

DESIGN FOR A BRACELET.

SPECIFICATION forming part of Design No. 12,370, dated July 19, 1881.

Application filed May 25, 1881. Term of patent 3½ years.

To all whom it may concern:

Be it known that I, ABIJAH WALLACE, of the city, county, and State of New York, have invented and produced a new and original 5 Design for a Bracelet, of which the following is a specification, reference being had to the accompanying drawings, in which—

Figure 1 is a perspective view of my newly-designed bracelet. Fig. 2 is a front elevation 10 of a bracelet with parts broken away to exhibit other parts illustrating my design. Fig. 3 is a front elevation of a portion of a bracelet, also illustrating my design.

Similar letters of reference indicate corresponding parts.

15 The leading feature of my design consists in a vertically-barred outer face combined with rounded edges and a horizontally-barred inner face, in which the vertical bars terminate.

20 The bracelet is preferably formed from long flat sheets of metal, hard rubber, or other suitable material, having a series of parallel cross-cuts or openings, *a*, made in it, so as to leave edges or longitudinal bars *A A*, connected by

25 a series of narrow cross-bars, *B B*. Then the said sheet is bent longitudinally near both edges to form the bracelet of the design here-

in shown, wherein the bars *A A* form the inner horizontal parallel bars of the bracelet, with an open space, *b*, between them, and the 30 bars *B B* form the vertical bars forming the front of the bracelet, while their bends form the rounded bracelet edges *C C*. These bars *B B* may be bent outward, so as to present a convex outer face to the bracelet and full 35 rounded bracelet edges, as shown in Fig. 1; or they may be flattened, as shown in Fig. 2, so as to present narrow rounded bracelet edges; and they may be formed with their own edges zigzagged, as shown in Fig. 3, or of any other 40 desired outline.

Having thus described my invention, I claim as new and desire to secure by Letters Patent—

The design for a bracelet herein shown and 45 described, the same consisting of the inner horizontal bars, *A A*, the outer vertical parallel bars, *B B*, and the rounded bracelet edges *C C*.

ABIJAH WALLACE.
